DISPLAY CABINET FOR EYEGLASS FRAMES
OR THE LIKE

Milan Arent, 9 Iroquois St., Worcester, Mass. 01602

Filed Oct. 17, 1968, Ser. No. 14,039

Term of patent 14 years

Int. Cl. D6—04

U.S. Cl. D6—168

FIG. 1

FIG. 2

FIG. 3

FIG. 4

FIG. 5

FIG. 6

FIG. 7

Fig. 1 is a perspective view of a display cabinet for eyeglass frames or the like, showing my new design;

FIG. 2 is a front elevational view thereof;

FIG. 3 is another front elevational view thereof;

FIG. 4 is a top plan view thereof;

FIG. 5 is a bottom plan view thereof;

FIG. 6 is an elevational view taken from the left end thereof; and

FIG. 7 is an elevational view taken from the right end thereof.

I claim:

The ornamental design for a display cabinet for eyeglass frames or the like, substantially as shown and described.
